US00D869242S

(12) **United States Design Patent** (10) **Patent No.:** **US D869,242 S**
(45) **Date of Patent:** **** Dec. 10, 2019**

(54) **DISPENSER FOR SPICE AND SEASONING**

(71) Applicant: **Abel Marquez**, Moody, TX (US)

(72) Inventor: **Abel Marquez**, Moody, TX (US)

(**) Term: **15 Years**

(21) Appl. No.: **29/608,561**

(22) Filed: **Jun. 22, 2017**

(51) LOC (12) Cl. **07-06**

(52) U.S. Cl.

USPC **D7/590**

Primary Examiner — Michael A. Pratt

CLAIM

The ornamental design for a dispenser for spice and seasoning, as shown and described.

DESCRIPTION

FIG. 1 is a left, front perspective view of a dispenser for spice and seasoning showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left elevational view thereof; and,

FIG. 7 is a right side elevational view thereof.

The broken lines shown in the figures depict portions of the dispenser for spice and seasoning that form no part of the claimed design.

1 Claim, 5 Drawing Sheets
